GEORGE M. BARROW, OF DERRY, PENNSYLVANIA, ASSIGNOR TO WESTINGHOUSE ELECTRIC & MANUFACTURING COMPANY, A CORPORATION OF PENNSYLVANIA

INSULATOR CONNECTER

Application filed April 9, 1927. Serial No. 182,208.

My invention relates to insulator connectors and particularly to connectors for insulators of the link type.

One object of my invention is to provide a connector of the above-indicated character that shall uniformly distribute the load forces thereof relative to an insulator for which it is adapted.

Another object of my invention is to provide a link insulator connector that shall permit the combined insulator and connector structure to be of reduced total length.

Another object of my invention is to provide a multi-turn endless connector element, for link insulators, that shall comprise novel reinforcing or seating means at its terminals and have its several turns effectively held together.

A further object of my invention is to provide a link-insulator connector that shall be simple and durable in construction, effective in its operation and economical to manufacture.

In insulators of the link type, considerable difficulty has been experienced in providing adequate connecting means therefor and certain objections have arisen, as a result of these difficulties. For instance, by reason of the relatively short horse-shoe or C-shape of the link portions of the connector and the desirability of keeping the insulator units relatively close to each other, difficulty has occurred in providing small strong terminal-attaching means for the links.

Terminal-attaching means have been suggested that are excessively large in proportion to the insulators, thus reducing the insulating character of the structure by an excess of metal.

Also, by reason of the curved interlinked openings in the insulators, single-strand links, which concentrate the load, serve to fracture the insulators under loads below the ability of the insulating material to withstand. Difficulty has also arisen in providing links and terminal-attaching means therefor that facilitate the handling and mounting thereof.

It is my aim to provide a link-insulator connector that overcomes the above-men-

tioned difficulties and objections and is an improvement over similar connectors heretofore employed or proposed.

Accordingly, in practicing my invention, I provide a multi-turn or filamentary endless link element in which the turns are so distributed, held together and reinforced as to overcome the objections and render the insulator and connector structure shorter, more economical and more effective than prior connectors of this general type.

Figure 1 of the accompanying drawings is a side view, partially in elevation and partially in section, of a plurality of link insulators that are attached to each other and provided with end terminals by connectors embodying my invention, and

Fig. 2 is an elevational view, taken at right angles to Fig. 1, the link insulators being removed and portions of one of the connectors being broken away for clearness.

The device comprises, in general, link insulators 2 and 3, end-terminal or connector structures 4 and 5 and an intermediate connector structure 6.

The insulators 2 and 3, which are of a usual and well-known type and, therefore, require no detailed description, comprise interlinked openings 8 and 9 having uniform cylindrical seat portions 10. The latter feature is slightly different from the laterally curved seats of the usual link insulator which are adapted to receive single-strand round links.

The end-connector elements 4 and 5 are similar, in that each comprises a channel member 12 that extends transversely to the insulator axis, but differ, in that the member 4 has a clevis portion 14 and the member 5 has an eye portion 15.

The elements 4 and 5 further comprise endless-link elements 17 that are disposed in the openings 9 and 8, respectively, of their respective insulators.

Each link element 17 is provided with enlarged or apertured loop ends 18 that are disposed in the channel member 12 and are secured in position by bolts 20 and cotter pins 21.

Each link element 17 comprises a plurality of helically-wound turns 22 of fila-

mentary material, such as wire, constructed in the form of a strap to fit a relatively great area of the cylindrical seat 9 or the seat 8 and to thereby more uniformly distribute load forces between the connector and the insulator than a single-strand link of round cross-sectional area.

The turns 22 are initially helically wound in the form of a flat-strap endless element or 10 ring and then bent to have portions 24 disposed in adjacent side-by-side relation and portions diverging therefrom and merging together again to form the loop ends 18.

The small ends of the individual filament 15 or wire of which the endless element is constructed are secured in position by welding to an adjacent turn of the wire or by clamping under one or two of metal reinforcing bands 25 which also serve to hold the turns in relative position.

The turns 22 may also be soldered, dipped in a metal bath, electrolytically coated together or otherwise suitably treated to retain their shape and relation to each other. These 25 treatments may further be combined in various combinations.

Tubular metal cylinders or sleeves 27 are provided in the loop ends 18 of the endless element 17 to reinforce the ends and to provide seats for the bolts 20. The sleeves may be welded or otherwise permanently secured in position.

The intermediate connector structure 6 is constructed similarly to the end connectors 35 4 and 5 and may comprise one endless-link element 17, as shown, having only two adjacent free loop ends 18. Otherwise, two endless elements, similar to the elements 17 of the end connectors 4 and 5 and having two pairs of 40 such ends between the insulators 2 and 3, may be employed.

In either case, these ends may be connected, as by links 29, bolts 30 and cotter pins 32 or by other suitable means.

45 While I have shown and described a particular form of my invention, changes may be effected therein without departing from the spirit and scope thereof, as indicated by the appended claims.

50 I claim as my invention:

1. A connector comprising an element constructed of wound wire in the form of an endless strap-like band folded to provide a single strap having a plurality of strap-like 55 layers in adjacent registering broad-side relation merging into a closed-loop portion, connecting said sections and means for holding the wire turns in said relation.

2. In combination, a link insulator having 60 a seat, and a connector having a portion of substantially C-shape embodying a wire section in the form of a strap of substantial width compared to its thickness linking the insulator with its broad side on the seat to 65 assume a shape closely conforming to the

seat under opposite tension on the legs of the C-shaped portion.

3. In combination, a link insulator having 70 a seat, and a connector linking the insulator comprising a wire-element in the form of a multi-layer strap having a broad side on, and conforming to, a portion of said seat and loop ends at the same side of the insulator each embodying a portion of one of said layers return bent into another layer. 75

4. In combination, a link insulator having a seat, and a connector linking the insulator on said seat comprising a helically-wound wire element in the form of a multi-layer 80 strap having a broad side conforming to a portion of said seat and loop ends at the same side of the insulator each embodying a portion of one of said layers return bent into another layer.

In testimony whereof, I have hereunto subscribed my name this 4th day of April, 1927.

GEORGE M. BARROW.
